UNITED STATES PATENT OFFICE.

JOHN C. BARBER, OF CHICAGO, ILLINOIS.

UNDERFRAME STRUCTURE FOR CARS.

1,138,615.

Specification of Letters Patent.

Patented May 11, 1915.

Application filed December 26, 1913. Serial No. 808,679.

To all whom it may concern:

Be it known that I, JOHN C. BARBER, a citizen of the United States, residing at Chicago, in the county of Cook and State of Illinois, have invented certain new and useful Improvements in Underframe Structure for Cars; and I do hereby declare the following to be a full, clear, and exact description of the invention, such as will enable others skilled in the art to which it appertains to make and use the same.

My present invention relates generally to railway cars, but is more particularly directed to the improvement of the underframe structure of freight cars of high carrying capacity.

Generally stated, the invention consists of the novel devices and combinations of devices hereinafter described and defined in the claims.

More specifically stated, the present invention is designed, particularly, as an improvement on the underframe structure of railway cars wherein the car body is supported from the trucks by four-point bearings located over or directly associated with the truck side frames, in contradistinction to that type of car body wherein the weight of the load is transmitted through center bearings applied between the central portions of the truck and body bolsters.

So far as the present invention is concerned, the so-called four-point bearings between the truck side frames and the car body may take various forms, but in most instances they will be in the nature of lateral motion side bearings such as those disclosed and claimed in the patent to Lake and Deverell, 798,350, of date August 29, 1905, entitled "Anti-friction bearing for cars," and in my own prior Patent, 875,565, of date December 31, 1907, entitled "Car truck," and in several of my subsequent patents.

As one of the chief features of novelty of the present invention, I provide a car body or platform with side sills that are located directly, or approximately, over the side frames of the car trucks, and between which and the side frames the anti-friction bearing device, preferably in the form of lateral motion side bearings, are interposed so that the weight of the load is transmitted from these side sills directly downward to the truck side frame. This novel relative arrangement of the side sills, truck side frames and

anti-friction bearing devices is disclosed and broadly claimed in my U. S. Patent 1,031,163, issued of date July 2, 1912, and entitled "Improved car construction." With this improved construction, the heavy center sills, usually provided at or approximately at the center of the car, may be entirely dispensed with, and the truck bolsters and body bolsters become subordinate elements and are not relied upon to transmit the weight of the load from the car body to the truck side frames, and, hence, in some instances may, possibly, be dispensed with.

Various other novel and important features of construction are involved in the present invention, all as will hereinafter be more fully disclosed.

In the accompanying drawings, which illustrate the invention, like characters indicate like parts throughout the several views.

Referring to the drawings:—Figure 1 is a side elevation with some parts broken away, showing the improved underframe construction of the car; Fig. 2 is a plan view of the parts shown in Fig. 1, some parts being removed and some parts being broken away; Fig. 3 is a transverse vertical section taken on the line $x^3 x^3$ of Figs. 1 and 2; Fig. 4 is a transverse section taken on the line $x^4 x^4$ of Figs. 1 and 2; Fig. 5 is a front end elevation of the underframe structure; Fig. 6 is a vertical section taken approximately on the line $x^6 x^6$ of Fig. 2, some parts being removed and some parts being shown in full; Fig. 7 is a fragmentary detail in vertical section taken on the line $x^7 x^7$ of Fig. 6; Fig. 8 is a fragmentary section taken longitudinally of the underframe structure on the line $x^8 x^8$ of Fig. 7; and Fig. 9 is a side elevation with some parts broken away, showing connections between the underframe structure and one of the car trucks.

The floor structure proper is preferably made of wood and the stake pockets (when employed) are preferably cast, but all of the other parts of the underframe structure are preferably of commercial steel, such as rolled steel plates, angle bars, channel bars, or I-beams. The main side sills or girders, which, as stated, are designed to be located over the truck side frames and may be constructed in various ways, are preferably made up of vertically disposed steel plates 1 and upper and lower pairs of angle bars 2 and 3 respectively. The plates 1

constitute the webs of the main sills or girders which extend from end to end of the car platform or body. The upper angles 2 have their top flanges extended in opposite directions and their vertical flanges riveted to the upper edges of the respective web plates 1. The lower angles 3 have their horizontal flanges both extended outward and their vertical flanges riveted to the lower edges of the respective web plates. By turning the flanges of the lower angles 3 outward, increased wheel clearance is obtained. The central portions of the web plates 1 are much increased in vertical dimensions so as to truss and very greatly strengthen the intermediate portions of the main side sills.

The body bolsters, as preferably constructed, are made up each of a pair of laterally spaced channel-beams 4, the outward turned top flanges of which are rigidly connected by large cover plates 5 riveted thereto. These cover plates increase in width toward the centers so as to increase the strength of the intermediate portion of the bolster, and for other reasons hereinafter noted. The bottom flanges of the bolster-forming channels 4 are riveted to tie plates 6 and to the flange of a central hub 7. This hub 7 is adapted to coöperate with a hub or pivot member, not shown, but which would be located on the central portion of the truck bolster. This pivotal connection between the body and truck bolsters, however, carries no part of the load but simply serves to hold or assists in holding the truck for proper radial movement in respect to the car body. The upper portions of the body bolster channels 4 are cut away at their ends so as to leave the said channel bars with reduced end portions 4^a that project outward beyond the main side sills and serve to support supplemental sills 8. These supplemental sills 8 are preferably in the form of channels with inturned flanges, the lower flanges thereof being riveted to joint channels 9, which, in turn, are riveted to the said end portions 4^a. The supplemental sills 8 are preferably extended the full length of the car body and their upper flanges are raised substantially to the underside of the floor 10, rivet head clearance only being left. The steel cover or connecting plate 11 extends the full length of the tops of the main and supplemental side sills and is riveted to the upper flanges thereof so that the two sills become practically one member. At suitable points longitudinally of the car, the side sills are further connected or tied together by transverse cross beams, best shown in Figs. 3 and 6. Each of these cross beams is shown as made up of an upper and a lower channel 12 and 13, both of which are shown as directly riveted to vertical joint angles 14, which, in turn, are riveted

to the web plates and angles of the main side sills. The channels 12 terminate between the web plates of the two side sills, while the lower channels 13 are extended through the said web plates, and their projecting ends are rigidly secured to the lower flanges of the supplemental sills 8, preferably by rivets and by interposed gusset plates 15, to cross beams. The two cross beams 12^a and 13^a, which are directly inward of the body bolsters, do not extend beyond the inside of the main sills on account of the lesser depth of the latter at those points, but the extension is here provided in the form of built up brackets 16 that are riveted to the web plates 1 and to the lower flanges of the supplemental sills 8, as best shown in Figs. 6 and 7.

At the ends of the car, the main and supplemental side sills are rigidly secured to and tied together by transverse end sills 17, preferably made up of channel bars and reinforcing angle bars, the said parts being usually connected by rivets. The ends of the end sills 17 are rigidly connected to the ends of the supplemental side sills 8 by corner brackets 18 (see particularly Figs. 2 and 6).

The draft sills 19, at their inner ends, are rigidly connected to the body bolsters 4 and to the upper and lower cover plates of the said body bolsters. At their outer ends, the said draft sills are rigidly secured to the end sills 17 by gusset plates 20 (see Fig. 2) and by angle strips 21 (see Fig. 6). Also, said draft sills, at their outer ends, are further connected to the said end sills by a casting or brackets 22 which serve as guides for a coupler draft bar 23 (see Figs. 1 and 2). Oblique braces 24 (see Fig. 2), preferably of channel form, are riveted at their ends to the top gusset plates 20 and to the truck cover plates 5 of the body bolsters, and further reinforce and stiffen the connection between the body bolsters and end sills and the draft sills and are effective under both bumping and draft strains, and assist in transmitting such bumping and draft strains from the coupler draft bar to the side sills.

At suitable intervals along each side of the underframe structure, metallic (preferably cast) stake pockets are secured to the outer sides of the supplemental sills 8. These stake pockets, at their upper extremities, terminate approximately flush with the top of the floor 10, and, at their outer faces, they terminate approximately flush with the outer edges of said floor, so that they cannot be engaged and torn off. These pockets 25, at their upper ends are shown as provided with inwardly projecting flanges 26 that rest upon and are riveted to the outer edges of the sill connecting plates 11, and also to the upper flanges of the segmental sills 8 (see

particularly Figs. 2 and 3). At the front and rear sides (see particularly Figs. 1 and 3), the stake pockets 25 are formed with projecting flanges 27 that terminate in lower end brackets 28, which latter are shown as riveted to the supplemental sills 8. The said flanges 27 and brackets 28 coöperate with the adjacent outer faces of the supplemental sills 8, and form pockets into which the ends 10 of wooden stringers or floor nailing strips 29 are seated. These stringers 29 are also preferably further secured to the supplemental sills 8 by transverse bolts 30, the locations of which are diagrammatically indicated in Fig. 1. The outer ends of the end members of the stringers 29 are seated in pockets 18^a (see Fig. 2) formed in the corner brackets 18.

The floor 10 is nailed to the stringers or strips 29 and to other or intermediate stringers or nailing strips 31 that are supported on and secured to the body bolsters 4, the upper members 12 and 12^a of the cross beams and on the intermediate portions of 25 the end sills 17.

As already stated, this improved car underframe structure may be supported from the truck side frames in different ways. However, in Fig. 9, one of the trucks is 30 shown as supporting the underframe structure through the intervention of lateral motion and radial or side bearing devices of the anti-friction or roller type, constructed and applied in the manner disclosed and claimed 35 in my U. S. Patent 1,014,362, issued of date January 9, 1912, and entitled "Car truck". These parts may, therefore, be very briefly noted as follows:—The numeral 33 indicates the truck wheels; the numeral 34 the truck 40 side frames; the numeral 35 a spring-supported truck bolster; and the numeral 36 indicates, as an entirety, the combined lateral motion and radial motion roller bearing devices. For the further purposes of this 45 case, it is only necessary to note that the roller caps or top members of the roller bearing devices 36 are engaged by and directly support laterally spaced bearing lugs 37 that are rigidly secured to the 50 overlying main sills and the overlying portions of the body bolsters. These bearing lugs 37 (see Figs. 4 and 9) embrace the top arch bar of the truck frame 34 with sufficient clearance to permit desired lateral 55 movement of the car body in respect to the other trucks.

With the above described construction, it will be noted that the load is transmitted from the car body or platform to the truck 60 side frames directly through the side sills and that the customary center sills are dispensed with. The present railway service demands freight cars of enormously high carrying capacity and to meet this demand 65 the underframe structure disclosed and

claimed was designed for a safe carrying capacity of one hundred and fifty thousand pounds. It has been found impracticable or inadvisable to design cars for such high carrying capacity on any plan which 70 contemplates carrying the load through truck and body bolsters acting as trusses in which the load is transmitted therethrough under a leverage action tending to bend the same. But with the present design, cars may be 75 designed for the above carrying capacity, and even for much greater carrying capacities because of the arrangement of the main side sills over the truck frames, whereby the load is transmitted directly to the truck 80 frames at four different points. Also, the bumping and draft strains transmitted through the coupler draft bars and draft sills are more evenly distributed throughout the car underframe structure than where 85 center sills were employed. Also, because of the improved manner of arranging the sills to transmit the load to the trucks, a maximum of strength is obtained with a minimum of metal, and, as is obvious, this results in the highest possible carrying capacity, strength, and durability at a minimum of cost.

What I claim is:—

1. A car underframe structure having 95 main side sills located for application over the truck side frame, body bolsters rigidly secured to and connecting said side sills and having continuous end portions projecting beyond the same, and relatively shallow 100 supplemental side sills supported by the projecting ends of said body bolsters.

2. A car underframe structure having main side sills located for application over the truck side frames, body bolsters rigidly 105 secured to and connecting said main side sills and having continuous end portions projecting beyond the same, relatively shallow supplemental side sills supported by the projected ends of said body bolsters, 110 and connecting plates secured to and tying together the upper portions of said main and supplemental sills.

3. In a car underframe structure, the combination with main side sills, of body 115 bolsters and cross beams connecting said side sills and having continuous end portions projecting beyond the same, relatively shallow supplemental side sills supported by the projected ends of said body bolsters 120 and cross beams, and cover plates rigidly connected to the upper portions of said main and supplemental side sills.

4. In a car underframe structure, the combination with main side sills, of body 125 bolsters and cross beams connecting said side sills and having continuous end portions projecting beyond the same, the tops of said body bolsters and cross beams being located below the tops of said side sills, rela- 130

tively shallow supplemental side sills supported by the projected ends of said body bolsters and cross beams, brackets secured to said supplemental sills, outside nailing strips mounted in said bracket, intermediate nailing strips carried on said body bolsters and cross beams, and a floor applied to said nailing strips.

5. In a car underframe structure, the

- 10 combination with main side sills, of body bolsters and cross beams connecting said side sills and having end portions projecting beyond the same, relatively shallow supplemental side sills supported by the projected ends of said body bolsters and cross beams, outside nailing strips secured to said supplemental sills, intermediate nailing strips carried on said body bolsters and cross beams, a floor applied to said nailing strips, and cover plates located immediately below said floor and rigidly secured to and tying together the upper portions of said main and supplemental sills.
- 15
- 20

6. A car underframe structure having side

- 25 sills made up of vertical web plates and top and bottom angles, said top angles having their horizontal flanges turned in reverse directions and their lower flanges riveted to the upper edges of said web plates, and the
- 30 said lower angles having their horizontal flanges both projecting outward and having their vertical flanges riveted to the lower edges of said web plates.

7. In a car underframe structure, the

- 35 combination with side sills made up of vertical web plates and top and bottom reinforcing angles, of vertical joint angles riveted to the said web plates, and metallic cross ties riveted to said joint angles, and having
- 40 continuous end portions that project through the said web plates.

8. In a car underframe structure, the

- 45 combination with side sills made up of vertical web plates and top and bottom reinforcing angles, of vertical joint angles riveted to the said web plates, metallic cross ties

riveted to said joint angles, and having end portions that project through said web plates, supplemental side sills supported on the projecting ends of said cross ties, and connecting plates between said top reinforcing angles and said supplemental side sills.

9. In a car underframe structure, the combination with side sills made up of vertical web plates and top and bottom reinforcing angles, of vertical joint angles riveted to the said web plates, metallic cross ties riveted to said joint angles, and having continuous end portions that project through said web plates, the tops of said cross ties being located in a plane below the tops of said side sills, supplemental side sills supported on the projecting ends of said cross ties, and connecting plates between said reinforcing angles and said supplemental side sills.

10. In a car underframe structure, the combination with side sills made up of vertical web plates and top and bottom reinforcing angles, of vertical joint angles riveted to the said web plates, metallic cross ties riveted to said joint angles, and having end portions that project through said web plates, the tops of said cross ties being located in a plane below the tops of said side sills, upper and lower connecting plates secured to said top reinforcing angles and the projecting ends of said cross ties, supplemental sills in the form of channels, having their flanges turned inward and riveted to said top and bottom connecting plates, brackets secured to the webs of said supplemental sills, outside nailing strips mounted in said brackets, intermediate nailing strips carried on said cross ties, and a floor applied to said nailing strips.

In testimony whereof I affix my signature in presence of two witnesses.

JOHN C. BARBER.
